(57) **CLAIM**

The ornamental design for a vehicle side mirror, as shown and described.

DESCRIPTION

FIG. 1 is a perspective view of a vehicle side mirror;
FIG. 2 is a front view of the vehicle side mirror;
FIG. 3 is a rear view of the vehicle side mirror;
FIG. 4 is a right-side view of the vehicle side mirror;
FIG. 5 is a left-side view of the vehicle side mirror;
FIG. 6 is a top view of the vehicle side mirror;
FIG. 7 is a bottom view of the vehicle side mirror; and,
FIG. 8 is a perspective view of the vehicle side mirror installed on each side of a vehicle.

In the drawings, the broken lines depict portion of the vehicle side mirror that form no part of the claimed design. The vehicle shown in broken lines is for environmental subject matter only and forms no part of the claimed design.
